JOHN H. GRAYSON, OF COLUMBUS, OHIO, ASSIGNOR TO RAYMOND N. RAUCH, OF COLUMBUS, OHIO, AND FRANK X. RAUCH AND F. D. FORSYTH, BOTH OF ATHENS, OHIO.

RAZOR-BLADE STROPPER.

Application filed December 3, 1926. Serial No. 152,366.

This invention relates to improvements in safety razor blade stroppers.

The principal objects of the present invention are:

5 First, to provide a stropper for safety razor blades, particularly the double edged type, comprising a holder in which the blade in either one of two positions of the holder is held positively in a certain position when 10 stroked on the strop and a predetermined cutting angle is maintained.

Second, to provide the blade holder with a single roller for determining the angle at 15 which the blade is held, which rolls on the strop instead of rubbing, only the hardened blade edge being allowed to rub on the leather strop so that there is no deposit of minute nickel flakes embedded in the strop as was the case in the use of other types of 20 razor blade stroppers with which I am familiar. The presence of the metallic flakes in the strop in such cases made it impossible to secure a fine, keen edge on the blades.

25 Third, to provide a blade holder of novel construction affording quick action in the matter of placing the blades therein or removing the same therefrom and also in reversing the blade to bring the both edges 30 of a double edged blade into stropping position or in bringing a single edged blade of the Gem type from the position in which it is placed in the holder to its stropping position.

35 The invention embraces still further objects and advantages to be referred to at greater length in the course of the following detailed description having reference to two forms of stroppers embodying my invention. The description has reference to 40 the accompanying drawings wherein—

Figure 1 is a side view of a stropper embodying the present improvements and designed for use with safety razor blades of 45 the double edged Gillette type;

Fig. 2 is a transverse section through the holder and its guide roller and is taken on the line 2—2 of Fig. 1;

50 Fig. 3 is an enlarged detail partly in elevation and partly in section showing the operation of the blade holder in placing or removing a blade;

Fig. 4 is a fragmentary elevational view

related to Fig. 3 showing the holder in closed position with a blade held therein; 55

Fig. 5 is a perspective view of parts of the blade holder shown in disassembled relation to better show the construction thereof; and

60 Figs. 6 and 7 are views corresponding to Figs. 1 and 2 of a stropper designed for use with a single edged blade of the Gem type. The same or similar reference numerals are applied to corresponding parts 65 throughout the views.

The stropper comprises a blade holder 10 forming part of a frame carried by a handle 11. The holder 10 comprises two narrow strips 12 and 13 hingedly connected at one end, as indicated at 14, whereby the strip 13 may be opened out, as indicated in Fig. 2, to receive a safety razor blade 15. Studs 16 are provided on the strip 12 to be received in openings in the blade 15 and also in openings 17 in the strip 13 when the holder is closed on the blade, as shown in Fig. 4. The strip 12 is mounted on the end of a rod 18 extending through the bore 19 of a ferrule 20 and through a hole 21 extending centrally through the handle 11. 70 The ferrule 20 has a drive fit in a counter bore 22 in the end of the handle 11 so as to form a rigid part of the handle. The rod 18 extends beyond the end of the handle 11, as shown at 23 in Fig. 1, to serve as a button to be pressed by the thumb to move the rod 18 lengthwise with respect to the handle 11 to bring the holder 12 to the open position shown in Fig. 3. The annular groove 24 provided on the handle 11 serves to receive the first two fingers when pressure is applied by the thumb to the end 23 of the rod 18. The ferrule 20 is slotted diametrically of the outer end thereof, as 80 shown at 25, to provide recesses for the reception of the ends of the strips 12 and 13 when the holder 10 is closed, as shown in Fig. 4. The ends of the strips 12 and 13 of the holder 10 are normally engaged in the slots 25 under the action of a pair of 85

spring arms 26 and 27. The former receives a pin 28 protruding from the end of the strip 12 and is riveted at 29 to one end of a pin 30 on which the roller 31 is mounted. The other spring arm 27 is 100 riveted, as at 32, to the other end of the

pin 30 and has a head portion 33 mounted on the ferrule 20. The head 33 is stamped to provide a flanged hub 34 bearing behind an annular flange 35 provided on the end of 5 the ferrule 20. The hub portion 34 of the head 33 is also slotted diametrically, as indicated at 36, to receive the ends of the strips 12 and 13 of the holder 10 substantially as shown in Fig. 4.

- 10 In operation, when a blade is to be placed in the holder, the projecting end 23 of the rod 18 is pressed in, as described above, against the action of the spring arms 26 and 27. This withdraws the ends of the 15 strips 12 and 13 from the slots 25 and 36, as shown in Fig. 3, sufficiently to permit the strip 13 to be opened out to place a blade in the holder or remove one therefrom. As soon as the blade is positioned on the studs 20 16, the holder is closed and thumb pressure is released from the end 23 of the rod 18 to permit the ends of the strips 12 and 13 to return into the slots 25 and 26, as seen in Fig. 4. The spring arms 26 and 27 25 accomplish this movement of the holder with the rod 18 and serve normally to retain the parts in this position. It will be observed that the double edged blade 15 has one of its edges in position for stropping. In Fig. 2, 30 a strop 37 is indicated in dotted lines and it will be noted that the roller 31 serves to hold the blade at a predetermined angle with respect to the strop. The proper cutting angle is, therefore, maintained when the 35 blade is stroked across the strop in the direction indicated by the arrow. In this movement of the strop nothing but the edge of the hardened blade is permitted to rub on the leather strop; the roller 31 rolls on the strop instead of rubbing. The fact that 40 the holder 10 is so narrow and grips the blade lengthwise of the middle thereof avoids any possibility of a part of the holder rubbing on the strop. In other stroppers, 45 with which I am familiar, a deposit of minute flakes of nickel or other metal was caused to be embedded in the strop. The presence of these metallic flakes made it impossible to secure a fine, keen edge on the 50 blade. At the end of each stroke the strop- 55 per is turned about on the roller for the return stroke, the roller 31 always preceding the blade and gauging the angle at which the same is held as it is stroked across the strop. After the first edge is stropped suffi- 60 ciently, the spring arm 27 is pulled over to the dotted line position shown in Fig. 1 to release the ends of the holder strips 12 and 13 from engagement in the slots 36 so that the holder may be turned with the handle through 180° to reverse the blade. The holder may be turned with the handle 65 relative to the arms 26 and 27 due to the fact that the ends of the holder strips re- main engaged in the slots 25 of the ferrule

20 which, as stated before, is rigid with the handle. The slots 36 thus serve as a clutch in holding the roller 31 in either of two operative positions with respect to the holder and the blade therein. In either of 70 these positions the blade, as shown in Fig. 2, is held in a plane passing through the axis of the roller 31. After both edges of the blade have been stropped, the blade may be removed by simply pressing in the projecting end 23 of the rod 18 as before. 75

In the slightly modified form of strop shown in Figs. 6 and 7 which is designed for use with single edged blades of the Gem type such as that shown at 15', all of the features hereinabove referred to are incorporated with the exception of the studs 16 and the opening 17 therefor provided in the holder 10. This is because blades of the Gem type have no openings therein but are provided with a heel portion 38 by means of which they are usually handled. I provide the holder 10 of two strips 12' and 13' having struck out portions 39 along the edges thereof on one side of the holder so as to provide between the same a recess in which the heel portion 38 of the blade may be received. In placing the blade in the holder, the cutting edge will be turned toward the roller 31, as indicated in dotted lines in Fig. 6, the heel portion 38 providing a place for finger pressure to properly line up the blade in the holder with the cutting edge substantially parallel with the roller. If it is desired, a blade after the same has 80 been stropped may be left in the holder in this position. After the blade is properly entered in the holder, the holder is reversed similarly as with the other type of strop to bring the edge of the blade into stropping 85 position. In this case, as in the other case, it will be observed that there is nothing but the edge of the hardened blade allowed to rub on the leather strop. The roller 31 rolls on the strop and maintains the blade 90 at the proper angle for stropping. The advantages of the type of strop first above described are secured to the same degree in 95 this modified or alternative type. 100

It is believed that the foregoing description conveys a clear understanding of my invention so that anyone skilled in this art will readily appreciate the many advantages and improvements offered by the present invention over what has been available heretofore. At the same time, it is believed to be clear that the invention is capable of embodiment in still other ways than shown by the two forms herein illustrated. All such modifications of the invention as come within the spirit and scope thereof it is the intention to cover in the appended claims. 115

I claim:

1. In a safety razor blade stropper, a handled frame, a single cylindrical roller 130

- mounted in said frame to roll on the strop in the operation of said strop, a holder for a blade in said frame alongside of and spaced from said roller, said holder being relatively narrow and extending lengthwise of the middle of the blade so as to be spaced appreciably from the sharp edge thereof, said holder being reversible by rotation on an axis parallel to the axis of the roller to bring the blade edge to be sharpened to that side of the holder away from the roller for sharpening, the roller being of such size that when rested on the strop only the blade edge to be sharpened can be brought into engagement with the strop, the holder being kept out of contact with the strop so as not to rub thereon in the stropping operation.
2. In a structure as set forth in claim 1, wherein the blade in either of its reversed positions is held in a plane passing through the axis of said roller so that the same cutting angle is maintained in stroking in either direction with the strop.
3. In a strop of the character described, a handled frame, a single cylindrical roller mounted in said frame slightly offset from but parallel with said handle, a blade holder in said frame disposed in spaced parallel relation to said roller approximately in line with said handle, said holder being reversible by rotation about an axis parallel to the axis of said roller to bring either edge of a double edged blade to that side of the holder away from the roller into stropping position or to bring the edge of a single edged blade into a similar position, and means at the end of said handle adjacent the end of said holder for holding the same in either of its reversed positions so that the plane of the blade held in the holder passes through the axis of the roller.
4. In a structure as set forth in claim 3 wherein the holder is provided with means for holding the same closed on a blade therein, and wherein the means for holding the blade holder in either of its reversed positions is independent of the means for keeping the holder closed whereby the holder may be reversed in its position without releasing the blade therefrom.
5. In a blade stropping device of the character described, a handle, a blade holder having a part extending lengthwise through said handle for mounting the holder thereon, said part being arranged to project from the end of said handle whereby the holder may be moved lengthwise with respect to said handle, spring means normally urging said holder to a retracted position comprising a spring arm bearing against the outer end of said blade holder to urge the same normally lengthwise toward the handle, said arm forming part of a frame carried by said handle having a roller mounted therein with its axis parallel to the blade holder serving to gauge the stropping angle for the blade received in said holder, said holder having a part arranged to be opened to permit the insertion of a blade in said holder, and a part provided on said handle providing jaws for the reception of said holder in its retracted position arranged to keep the holder closed.
6. In a structure as set forth in claim 5, wherein the spring arm has a pin mounted on the free end thereof in parallel relation to the blade holder having a gauging roller mounted thereon, a second spring arm extending between the other end of said blade holder and the opposite end of said pin.
7. In a structure as set forth in claim 5, wherein the spring arm has a pin mounted on the free end thereof in parallel relation to the blade holder having a gauging roller mounted thereon, a second spring arm extending between the other end of said blade holder and the opposite end of said pin, said last mentioned arm having means for holding the same rigidly in either one of two positions with respect to said handle for determining either of two operative positions of said holder with respect to the gauging roller.
8. In a blade stropping device of the character described, a handle, a blade holder mounted thereon, and a frame also carried by said handle and supporting a gauging roller in parallel relation to said blade holder, said frame having a part arranged to be locked in either one of two positions with respect to said handle for determining either of two operative positions of said roller with respect to said blade holder.
9. In a structure as set forth in claim 8, wherein the part of said frame for determining the operative positions of said roller with respect to said blade holder comprises a spring arm arranged to be flexed to release the same from either of its locked positions to permit rotation of the blade holder with respect to the roller to its other operative position, the tension of said spring arm serving to move the same to its locked position upon the arrival of the blade holder at its proper operative position.
10. In a blade stropping device of the character described, a handle, a blade holder mounted thereon capable of lengthwise movement with respect thereto to move the same to and from open position, spring means normally urging said holder to closed position, a part carried by said handle providing clutch jaws for holding said blade holder closed, a gauging roller in parallel relation to said blade holder, and a frame carried by said handle having said roller mounted therein, said frame comprising a spring arm having clutch jaws thereon also

arranged to receive a part of the blade holder whereby to hold said roller in pre-determined operative position with respect to said holder.

5 11. In a structure as set forth in claim 10, wherein said roller-carrying frame is mounted for pivotal movement with respect

to said handle to bring the roller to either side of said holder, the clutching jaws of said spring arm serving to retain the frame 10 in either of its adjusted positions.

In witness of the foregoing I affix my signature.

JOHN H. GRAYSON.
